UNITED STATES PATENT OFFICE.

EDWARD A. HALBLEIB, OF ROCHESTER, NEW YORK, ASSIGNOR TO NORTHEAST ELECTRIC COMPANY, OF ROCHESTER, NEW YORK, A CORPORATION.

ELECTRIC SWITCH.

1,010,753.

Specification of Letters Patent.

Patented Dec. 5, 1911.

Application filed December 16, 1910. Serial No. 597,729.

To all whom it may concern:

Be it known that I, EDWARD A. HALBLEIB, a citizen of the United States, and resident of Rochester, in the county of Monroe and 5 State of New York, have invented certain new and useful Improvements in Electric Switches, of which the following is a specification.

This invention relates to electric switches 0 of the type in which locking means are provided in order that unauthorized tampering with the switch may be prevented.

The object of the invention is to produce a device of this kind which is compact, simple and reliable, and, more particularly, to produce a switch provided with a plurality of operating devices or plugs, all of which may be simultaneously locked with each plug in either closed or open position, as the 20 case may be, so that the electrical apparatus controlled by the switch may be left in any required condition.

To the above ends the invention consists in the electric switch hereinafter described, 25 and illustrated in the accompanying drawings, as it is defined in the succeeding claims.

In the drawings:—Figure 1 is a vertical section, seen from the front of the switch, on the line 1—1 in Fig. 2; Fig. 2 is a horizontal section, on the line 2—2 in Fig. 1; Fig. 3 is a horizontal section, on the line 3—3 in Fig. 1; and Fig. 4 is a vertical section, on the line 4—4 in Fig. 1, looking from left to right in the latter figure.

The illustrated embodiment of the invention is a switch particularly adapted for use in connection with a motor-vehicle, for controlling the various circuits thereon through which the electric lights, the ignition devices, the horn &c. are energized. It is illustrated as provided with four switch-plugs 5, though obviously the number may be increased or diminished to any required extent. Each of the switch-plugs 5 consists of 40 a round rod of insulating material, arranged in vertical position and provided with an enlarged head 6 which may be marked on its upper surface to indicate the circuit controlled by the plug. These plugs may be

reinforced by central metal rods, as shown 50 in Figs. 2 and 3. The switch-plugs are arranged to slide vertically through openings in the upper and lower walls of a casing 7 by which all parts of the switch-mechanism are inclosed, except the upper and lower extremities of the switch-plugs. Each plug 55 coöperates with two contact-springs 9 which engage the plug on opposite sides. These springs are made of resilient sheet-metal, and are fixed at their rear ends, by means 60 of screws 11, to a base-plate 12 of insulating material. Each contact-spring has an inwardly-convex extremity 13 resiliently engaging the corresponding switch-plug, and the switch-plug carries a movable contact-member 15 in the form of a ring of metal 65 provided with an annular concave surface, as shown in Fig. 1.

In the drawings the switch-plugs are all shown in depressed, open-circuit position, 70 but when any one of the plugs is raised, by pressure against its lower end, the contact-ring 15 is brought into position between the contact-springs 9, thereby making electric connection between them and thus closing 75 the circuit of which they are a part. The form of the contact devices is such as to retain the switch-plug in elevated position until it is depressed again by pressure on its upper end. To secure a firm engagement of 80 the contact-springs with the plugs, each contact-spring is backed by a spring 14, of the form shown in Fig. 2, which is also secured against the base 12 by means of the screw 11. Each of the contact-springs is downwardly 85 extended at its rear end and provided with a binding-screw 16 by which it may be connected with the wires of the circuit of which it forms a part.

The means for locking the switch-plugs 90 comprise a locking-bar 17 which is wide and flat, and is arranged in horizontal position. This bar is provided with a series of openings 18 of an approximately oval or key-hole form, and the switch-plugs pass 95 through these openings. Each switch-plug is provided with two annular grooves 19 and 21, respectively, and the shoulders

formed by these grooves constitute abutments to coöperate with the locking-bar. When the locking-bar is moved longitudinally to its right-hand position the plugs 5 slide freely through the large left-hand portions of the openings, but when the locking-bar is in its left-hand position, as illustrated, it is adapted to coöperate with the abutments just referred to, thereby preventing 10 movement of the switch-plugs. When the switch-plugs are in their lower open-circuit position, as illustrated, they are normally retained in this position by the engagement of the contact-springs with annular depressions 20 in the plugs, and in this 15 position of the plugs the locking-bar engages the grooves 19 in the plugs. When any of the plugs is in raised or closed-circuit position it is adapted to be locked in this 20 position by the engagement of the locking-bar with the groove 21.

The locking-bar is supported, near its ends, in bearings formed in vertical partitions 22 and 23 near the ends of the casing 7. The 25 bar is free to slide longitudinally in these bearings, but is normally held in its left-hand position by means comprising an upwardly-bent lug 24 at its left-hand end and compression springs 25 engaging this lug 30 and the partition 22. The locking-bar is thus normally retained in locking position.

The switch is unlocked by means of a key 26 (Fig. 4) which is inserted through a key-hole 27 in the casing. The extremity of the 35 shank of the key enters a metal socket 28 embedded in the base-plate 12. This key is provided with wards 29 which are adapted to engage the lug 24, when the key is turned to the right, thereby forcing the locking-bar 40 to the right and into unlocked position. A block 31 provided with irregular upper projections is secured beneath the position occupied by the key, so as to coöperate with the wards and prevent the use of a key not 45 designed for the switch. A plate 32 fixed adjacent to the block 31 projects upwardly, so that its upper edge serves as a stop for the wards 29 when the key has been turned to unlocking position. So long as the key 50 is left in the lock in the position described the switch may be freely used, any one of the switch-plugs being movable into either position. When the key is turned again to the left and withdrawn, however, the locking-bar 55 is moved to the left by the springs 25 and thus locks all of the plugs simultaneously, each plug being locked in either upper or lower position, as it may happen to have been left by the operator. To support 60 the locking-bar, between its ends, against any forcible attempt to move one of the switch-plugs when locked, a horizontal partition 33 is arranged in the casing close to the upper surface of the locking-bar, and

this partition serves also to inclose the contact-devices in a compartment by themselves. The locking-bar is supported from beneath by means of short vertical partitions 30 in the casing.

The base-plate 12 is provided with openings 34 through which screws or bolts may be passed to secure it upon the dash-board of an automobile, or upon any convenient support, and the casing 7 is removably secured in place by means of screws 35 threaded into both the base-plate and the support. The arrangement of the parts is such that upon removing the screws 35 the casing may be removed, together with the locking mechanism and the switch-plugs, 80 while the contact-springs are left undisturbed upon the base-plate.

I am aware that electric switches have been proposed heretofore in which means are provided for locking the contact-devices 85 against unauthorized operation, but, so far as I am aware, I am the first to produce a switch of this type in which a plurality of switch-members may be locked simultaneously and particularly in which such members may be locked in either open-circuit or closed-circuit position.

I claim:

1. An electric switch having, in combination, a longitudinally-movable key-operated locking-bar, switch-plugs arranged transversely to the locking-bar and movable longitudinally into two positions, the plugs having locking abutments for engagement with the bar in both longitudinal positions of the plugs, and means for retaining the plugs 100 yieldingly in both longitudinal positions when the locking-bar is not in locking engagement with the plugs.

2. An electric switch having, in combination, a longitudinally-movable key-operated locking-bar, switch-plugs arranged transversely to the locking-bar and movable longitudinally into two positions, the plugs having locking abutments for engagement with the bar in both positions of the plugs, and resilient contact-devices engaging the plugs and retaining them yieldingly in both longitudinal positions.

3. An electric switch having, in combination, a series of independently-movable switch-members, a key-operated locking-member coextensive with said series of switch-members and movable into and out of locking engagement with all of said members simultaneously; each switch-member having locking-abutments for engagement with the locking-member in each position of the switch-member, and means for retaining each switch-member yieldingly in each position when the locking-member is not in operative position.

4. An electric switch having, in combina-

tion, a longitudinally-movable key-operated locking-bar having an aperture therein, a switch-plug extending through said aperture and longitudinally movable there-
5 through, the plug having a plurality of grooves for locking engagement with the locking-bar, adjacent said opening, in the

several positions of the plug, and resilient contact-devices engaging the plug and retaining it yieldingly in its several positions.
